UNITED STATES PATENT OFFICE

CARL E. NORIN, OF JERSEY CITY, NEW JERSEY, ASSIGNEE TO UNDERWOOD ELLIOTT FISHER COMPANY, OF NEW YORK, N. Y., A CORPORATION OF DELAWARE

TYPEWRITING MACHINE

Application filed July 8, 1927. Serial No. 204,274.

This invention relates to fractional line-spacing mechanism for typewriting machines.

The object is to produce an improved mechanism readily applicable to different types 5 of machines, for allowing the operator to rotate the platen, at will, through a fraction of the regular line-space forwardly or rearwardly.

The mechanism includes a toothed wheel, 10 which is fixed to the platen-shaft, and, further, a hand-operated lever adjacent the toothed wheel, having a slot-and-screw connection to the platen-frame, for a longitudinal movement of the lever. Due to the slot- 15 connection a tooth upon the lever may be brought into interlocking engagement with a tooth space of said wheel so that the platen may be conveniently rocked for a partial line-spacing as required by a full operation of the 20 lever. When subsequently the lever is returned to neutral, the platen is restored simultaneously to initial line-position, by the camming action of the usual detent-roll upon the teeth of the regular line-space wheel.

25 A stop arrangement for said lever constitutes a particular feature of the invention and includes self-centering seats provided on the lever to seat upon the platen-shaft and determine the normal and line shift positions 30 of the lever.

Another feature lies in means for adjusting the teeth of the fractional line-space wheel to the teeth of the regular line-space wheel without disturbing a prior permanent 35 assembly of the regular line-space wheel and finger-knob upon the platen-shaft.

Other features and advantages will herein-after appear.

In the accompanying drawings,

40 Figure 1 is a plan showing the fractional line-spacing device at the right-hand end of the platen.

Figure 2 is a side view upon the right-hand side of the platen-carriage taken at Figure 1 45 with the knob broken away to fully show the fractional line-spacing mechanism and its attachment to the platen and platen-frame, with the actuating lever in neutral position, its movement for working position, however, 50 indicated in dot and dash.

Figure 3 is a view similar to Figure 2 with parts broken away to show the actuating lever positioned for exponent writing.

Figure 4 is a similar view showing the actuating lever in position for subscript writing. 55

Figure 5 is a part sectional perspective disclosing means for adjusting the fractional device.

Figure 6 is a perspective with parts in line but drawn apart so as to clearly show the 60 details of the fractional line-spacing mechanism and their relation to each other.

The type-bar 1 prints upon a platen 2 whose shaft 3 is journaled in a platen-frame 4, said shaft having at the right-hand side a knob 5 65 fixed thereon.

The line-space mechanism at the left-hand end of the platen includes the usual ratchet-wheel 6 and detent 7.

A novel toothed wheel 8 may be secured to 70 the right-hand portion of the platen-shaft 3 by a set screw 9. A fraction-spacing lever 10 is placed between said wheel and the platen-frame and loosely mounted upon the platen-frame to actuate said wheel, together with the platen-shaft. The lever has a finger-piece 11 and a tooth or dog 12 to engage between the teeth of the wheel 8. The lever 10 is further provided with slot 13, through which passes

shouldered screw 14 threaded into the platen-frame, allowing the tooth 12 upon the lever to be shifted into and out of engagement with the wheel 8. In addition to this longitudinal sliding movement of the lever, a swinging movement at right angles to the platen has to 80 be performed, for turning the wheel backwardly or forwardly. An opening 14^a cooperates with the platen-shaft which passes through the opening. The shaft limits the movement of the lever and, at the same time, locks said lever in place when operated. To this end, the opening 14^a is formed with three notches or seats 15, 16 and 17 to fit over and seat upon the platen-shaft. The 85

middle notch 16 is deeper and confines the lever to its neutral position. The adjacent notches, upon engagement with the platen-shaft, serve to position and hold the lever 10 for exponent and subscript writing respec- 100

tively. The lever in its different shift positions is retained by spring 18 urging the notches into engagement with the platen-shaft, said spring fastened to the platen-frame by screw 19 and hooked at 20 to the lower end of the lever 10. The screw 19 may conveniently serve as a fastening for the usual draw band.

The teeth of the wheel 8 are equal in number to the teeth of ratchet-wheel 6, and the relative arrangement between the two sets of teeth and the lever is such that, when the wheel 8 is properly detained in normal printing-line position, an opening between two teeth of the wheel 8 will be brought opposite the engaging pin or tooth 12 of the lever 10 which then is in neutral or inoperative position. To obtain this adjustment, a square block or lug 21 is rigidly secured to said wheel 8 and held between the ends of screws 22 threaded into posts 23 which are shown to be integral with the platen-knob 5. Therefore when the wheel 8 is loosened upon the platen-shaft by withdrawing the screw 9, the wheel 25 may be given a very fine rotary adjustment by loosening up on one screw 22 and tightening up on the other screw 22 or vice versa, and the screw 9 reset, with the lever 10 in neutral position, i. e., notch 16 seated upon the platen-shaft and a space between two teeth of the wheel 8 is brought in line with the tooth 12 upon said lever.

The operation of the fractional line-spacing mechanism is performed by pulling the lever 10 forwardly against spring tension 18 from its neutral position, as indicated in Figure 2, so as to position the pin between teeth of the wheel 8 and simultaneously disengage the middle notch 16 from the platen-shaft. The lever is now at liberty to be shifted forwardly or backwardly according to the operator's desire to seat one of the adjacent notches 15 or 17 upon the shaft, where the lever may be held in place by said spring 18. In Figure 3 the lever is shown to be positioned for exponent writing while in Figure 4 its position for subscript writing is illustrated. In Figure 5 subscripts and superscripts are shown which may be obtained by using the novel device.

It will be seen that the device is compact and simple, and especially convenient in operation, since the entire shift operation is performed by manipulating a single finger-piece in a direction convenient to the operator. On account of the particular arrangement of the notches 15, 16 and 17, the mere shifting from one notch into another notch 60 serves to guide the actuating lever into or out of engagement with the shaft. Furthermore, the flatness or compactness of the whole arrangement is of special benefit where the space for attachment is restricted.

65 It will be understood that the wheel 8 may

be loose on the shaft 3 and that the two screws 22 may be permanently set on opposite sides of the lug 21 and the screw 9 eliminated.

Variations may be resorted to within the scope of the invention, and portions of the improvements may be used without others.

Having thus described my invention, I claim:

1. In a typewriting machine, the combination with a carriage having a platen, a platen-shaft and a line-space mechanism of a fractional line-space mechanism to rotate the platen in two directions a distance less than a line-space, including a toothed wheel rotatable with the platen, a lever having a clearance hole for the shaft, a projecting dog on the lever operable to engage between the teeth of the wheel, said lever actuatable diametrically of the platen across the shaft to bring the dog and teeth of the wheel into interlocking engagement and then actuatable to rock the platen, and self-centering seats formed in the shaft-clearing hole of the lever, to seat upon the shaft and determine the forward and backward stroke of the lever for fractionally line-spacing the platen for typing.

2. In a typewriting machine, the combination with a revoluble platen having a shaft, a line-space-mechanism for the platen, and a platen-frame in which said shaft is journaled, of fractional line-spacing mechanism including a toothed wheel mounted to rotate together with the platen, a lever loosely mounted upon said platen-frame and operating at right angles to the platen-axis and having a projection, said lever actuatable so that the projection may be brought to operatively engage the toothed wheel for rotation of the platen, and stops upon said lever to engage the platen-shaft in limiting the forward and backward stroke of the lever, when engaged with said wheel, to less than a line-space in the rotation of the platen.

3. In a typewriting machine, the combination with a revoluble platen having a shaft, a line-space-mechanism for said platen, and a platen-frame in which the shaft is journaled, of fractional line-spacing mechanism including a toothed wheel mounted to rotate together with the platen, a lever operating in a plane at right angles to the platen-axis and having at its lower end a slot-connection to the platen-frame, a tooth upon said lever, a finger-piece at the upper end of said lever, whereby to actuate the lever so that the projection operatively engages the toothed wheel, for rotation of the platen, and stops disposed midway upon the lever and engaging with the platen-shaft in limiting the stroke of the lever to less than a line-space in the rotation of the platen.

4. In a typewriting machine, the combination with a revoluble platen having a shaft,

- a line-space-mechanism for said platen, and a platen-frame in which said shaft is journaled, of fractional line-spacing mechanism including a toothed wheel mounted to rotate together with the platen, and a lever loosely mounted upon the platen-frame, said lever operating in a plane at right angles to the platen-axis and actuatable so as to bring a projection provided upon said lever into operative engagement with said toothed wheel for rotation of the platen and having an opening, said opening substantially formed with notches to engage the platen-shaft in determining the shift of the lever for neutral position and for rotation of the platen backwardly and forwardly, respectively, a distance less than a line-space. 5. In a typewriting machine, the combination with a revoluble platen having a shaft, a line-space-mechanism for said platen, and a platen-frame in which said shaft is journaled, of fractional line-spacing mechanism including a toothed wheel mounted to rotate together with the platen, a lever loosely mounted upon the platen-frame, said lever operating in a plane at right angles to the platen-axis, actuatable so as to bring a projection upon said lever into operative engagement with the toothed wheel for rotation of the platen, and a detent device to determine the lever in its shift-positions, including notches upon said lever to co-operate with a projection upon the platen-frame and a spring acting longitudinally upon the lever to hold the lever engaged in its respective shift-positions with said projection. 6. In a typewriting machine, the combination with a revoluble platen having a shaft terminating in a knob solidly fixed to said shaft, a line-space-mechanism for said platen, and a platen-frame in which said shaft is journaled, of fractional line-spacing mechanism including a toothed wheel to rotate together with the platen and mounted upon said shaft between said frame and said knob, a lever between said frame and said toothed wheel, operating at right angles to the platen-axis and loosely mounted upon the platen-frame and actuatable so as to bring a projection provided upon said lever into operative engagement with said toothed wheel for rotation of the platen, means to determine the shift of the lever for neutral position and for rotating the platen forwardly and backwardly, respectively, less than a line-space, and means for adjusting the toothed wheel relatively to the platen for proper co-operation with the line-space-mechanism, whereby a projection rigidly secured upon the toothed wheel is held between the ends of two screws, which are threaded into corresponding projections provided upon said knob, said screws to be operated for rotary adjustment of the toothed wheel. 7. In a fractional line-spacing mechanism for typewriting machines, the combination with a rotatable platen and a line-space wheel therefor, of a fractional line-space lever mounted for endwise displacement and settable to idle during normal rotation of the platen or to engage the line-space wheel to move the same backwardly and forwardly, a stop-means for limiting to less than a single line-space interval the backward and forward movements of the lever, and means mounted to urge the lever constantly endwise against the stop so that the latter is effective to hold the lever against displacement from settable positions thereof. 8. In a fractional line-spacing mechanism for typewriting machines, the combination with a rotatable platen and a line-space wheel therefor, of a fractional line-space toothed lever mounted for endwise displacement and settable to idle during normal rotation of the platen or to engage the tooth thereof with the line-space wheel to move the same backwardly and forwardly, a stop-means for limiting to less than a single line-space interval the backward and forward movements of the lever, and means mounted to urge the lever constantly endwise against the stop so that the latter is effective to hold the lever against displacement from settable positions thereof. 9. In a fractional line-spacing mechanism for typewriting machines, the combination with a rotatable platen and a line-space wheel therefor, of a fractional line-space lever mounted for endwise displacement and settable to idle during normal rotation of the platen or to engage the line-space wheel to move the same backwardly and forwardly, a stop-means for limiting to less than a single line-space interval the backward and forward movements of the lever, and tensionable means mounted to urge the lever constantly endwise against the stop so that the latter is effective to hold the lever against displacement from settable positions thereof. 10. In a fractional line-spacing mechanism for typewriting machines, the combination with a rotatable platen and a line-space wheel therefor, of a fractional line-space detent-lever mounted for endwise displacement and settable to idle during normal rotation of the platen or to engage the line-space wheel to move the same backwardly and forwardly, a stop-means engageable by a detent of the lever for limiting to less than a single line-space interval the backward and forward movements of the lever, and means mounted to urge the lever constantly endwise to engage the detent with the stop so that the latter is effective to hold the lever against displacement from wheel-moving position. 11. In a fractional line-spacing mechanism for typewriting machines, the combination with a rotatable platen and a line-space wheel therefor, of a fractional line-space

detent-lever mounted for endwise displacement and settable to engage the line-space wheel to move the same backwardly or forwardly, a stop-means engageable by a detent of the lever for limiting to less than a line-space interval the backward and forward movements of the lever, and means mounted to urge the lever constantly endwise to engage the detent with the stop so that the latter is effective to hold the lever against displacement from wheel-moving position.

12. In a fractional line-spacing mechanism for typewriting machines, the combination with a rotatable platen and a line-space wheel therefor, of a fractional line-space multiple detent-lever mounted for endwise displacement and settable to idle during normal rotation of the platen or to engage the line-space wheel to move the same backwardly and forwardly, a stop-means engageable by a detent of the lever for supporting the latter in idling position, said stop-means also engageable by another detent of the lever for limiting the backward and forward movements of the lever, and means mounted to urge the lever constantly endwise to engage any selected detent thereof with the stop so that the latter is effective to hold the lever against displacement from settable positions thereof.

13. In a fractional line-spacing mechanism for typewriting machines, the combination with a rotatable platen having a shaft, of a fractional line-space wheel mounted for rotation with the shaft, a fractional line-space lever mounted for endwise displacement in a direction radially of the shaft and settable to idle during rotation of the platen or to engage the line-space wheel to move the same backwardly and forwardly, a detent on the lever to engage the shaft and limit to less than a single line-space the backward and forward movements of the lever, and means mounted to urge the lever constantly endwise to engage the detent with the shaft so that the latter is effective to hold the lever against displacement from settable positions thereof.

14. In a fractional line-spacing mechanism for typewriting machines, the combination with a platen-shaft having a line-space wheel, of a knob secured upon the shaft to turn the platen, a fractional line-space toothed wheel loosely mounted on the shaft adjacent the knob, interfitting devices mounted on the knob and the fractional line-space wheel effective to adjust the loose wheel to the fixed knob and time the teeth of the fractional line-space wheel with the teeth of the line-space wheel, and further effective to permanently lock the adjusted fractional line-space wheel to the knob, and a settable fractional line-space lever mounted for endwise movement to engage a lined-up tooth-

position of the fractional line-space wheel and then rock the platen in either direction to a lever-seating position and hold the platen in a fractional line-spaced position for typing.
